CLAIM

The ornamental design for the bill portion of a sun visor, substantially as shown and described.

DESCRIPTION

FIG. 1 is a top plan view of a bill portion of a sun visor, showing our new design;

FIG. 2 is a front elevational view thereof;

FIG. 3 is a left end elevational view thereof, the opposite side being substantially a mirror image thereof;

FIG. 4 is a bottom plan view thereof.

The broken line showing of the crown portion and headband portion are for illustrative purposes only and do not form part of the design.
